UNITED STATES PATENT OFFICE.

NELLIE F. JAYNE, OF BROOKLYN, NEW YORK.

LIFEBOAT.

Application filed January 30, 1923. Serial No. 615,852.

To all whom it may concern:

Be it known that I, NELLIE F. JAYNE, a citizen of the United States, and residing in Brooklyn, county of Kings, and State of New York, have invented certain new and useful Improvements in Lifeboats, of which the following is a specification.

This invention relates to life saving apparatus and has more special reference to a construction for affording means for preventing the stowing in of life boats while being lowered in a high sea. In its more limited aspect the invention comprehends a skeleton frame having in general a configuration corresponding to the shape of the particular life boat with which the frame is to be used, the frame comprising resilient buffer elements adapted to cushion the shock of the impact of the boat and sides of the vessel. In carrying out the invention it is contemplated providing the skeleton frame with suitable means for affording a hold to the passengers in the event of the overturning of the boat so that they may readily cling to the boat sides with some chance of being rescued. Specifically, these means comprehend pivoted rings secured to the frame each of which is preferably provided with a float to maintain it in position so that it may be readily grasped when the boat is overturned. It is further contemplated arranging the skeleton frame in such a manner that it may be cast off when once the boat is safely lowered and no further need for the device appears necessary to the boat occupants.

The drawing accompanying this specification and forming part thereof illustrates one of the contemplated embodiments of the invention, to illustrate the underlying principles of the invention so that they may be readily comprehended by those skilled in the art and is not intended as limiting the invention to the precise form disclosed.

In said drawing:

Fig. 1 is a side elevation of the invention and,

Fig. 2 is a vertical section of the invention.

Continuing now by way of a more detailed description, a skeleton frame indicated in its entirety by A comprises a false keel A', which is carried upwardly at the bow and stern in the manner indicated. The keel A' has a sufficient number of upstanding ribs B, hinged thereto at C to afford adequate protection to the boat. This skeleton struc-

ture conforms in general to the shape of the particular life boat with which the frame is to be used, as will be readily understood. Each of the ribs B may be and preferably is provided with one or more rings or handholds B', which preferably consist of rope loops, although of course rings of any suitable material might be utilized. Each of these rings may be and preferably is provided with wood or cork floats E to maintain the rings in spaced relation with the frame so in the event that the boat overturns a convenient hand hold may be afforded to the occupants.

As heretofore indicated the ribs B are hinged at one end to the false keel and in order to afford a cushioning to the impact which occurs when the boat is swept against the vessel's sides, particularly when the life boat is being lowered in a high sea, the upper ends of these ribs have a cushioning means interposed between a gunwale strip F forming part of the frame A and the upper ends of the ribs. Specifically these cushioning means take the form of coiled springs G carried on posts H which latter engage suitable openings in the ribs B and afford means for preventing displacement of the ribs B. The posts H are preferably secured to the gunwale strip F, although of course they might be directly secured to the boat sides in any convenient manner. These posts preferably have enlarged ends J to prevent the ribs from leaving the posts H.

Evidently the frame may prove an obstruction to the navigability of the boat and to this end the frame is provided with pivoted arms K normally overlying the boat gunwale and secured to the frame A, which maintain the frame A in position until released. The release of these arms from the boat gunwale permits the frame to become detached from the boat and sink into the water when the boat has once been safely launched, and no further need for the frame appears necessary to the boat occupants.

It is claimed:

1. A skeleton life boat frame adapted to conform to and fit over a life boat and comprising independently movable ribs normally spring pressed outwardly and a keel to which the ribs are hinged.

2. A skeleton life boat frame adapted to fit over a life boat and comprising a false keel, upstanding ribs hinged to the keel, a gunwale strip and springs located between

the upper end of said ribs and the gunwale strip.

3. Means for preventing the "stoving in" of life boats comprising a false keel adapted to underlie the keel of a life boat, upstanding false ribs hinged at one end to the keel and having pin receiving openings, a gunwale strip having projecting pins adapted to engage said openings, coiled springs sur-

rounding said pins and bearing against said ribs and means associated with the gunwale strip to normally maintain the false work in position on the boat until released.

Signed at the city of New York, in the county of New York and State of New York, this 16th day of October, 1922, A. D.

NELLIE F. JAYNE. [I. S.]
